UNITED STATES PATENT OFFICE.

FRANK D. WINKLEY, OF MADISON, WISCONSIN, ASSIGNOR TO MADISON-KIPP LUBRICATOR COMPANY, OF MADISON, WISCONSIN, A CORPORATION OF WISCONSIN.

LUBRICATOR.

1,267,302.

Specification of Letters Patent. Patented May 21, 1918.

Application filed January 8, 1917. Serial No. 141,312.

To all whom it may concern:

Be it known that I, FRANK D. WINKLEY, a citizen of the United States, residing at Madison, in the county of Dane and State of Wisconsin, have invented a certain new and useful Improvement in Lubricators, of which the following is a specification.

My present invention pertains to force feed lubricators and has reference more particularly to the provision of means for adjusting and controlling the flow of oil, the means being such as to prevent the parts from being brought into such position as will cut down the amount of oil fed below a predetermined minimum, while at the same time allowing free adjustment for a greater flow or feed.

In the use of force feed lubricators upon machines, and more especially upon automobiles, where adjustment of the parts frequently falls into inexperienced hands, there is a possibility of the user adjusting the lubricator so as to cut off the oil-supply, or reduce it to a point below which it will not effectively lubricate the parts to which the oil passes.

It is the object of this invention to provide an inaccessible, adjustable lock or stop for the feed-controlling means of the lubricator, which lock may be initially set by one skilled in the art of lubrication, and which, while permitting adjustment for greater feed, will prevent such adjustment as would cut the feed down below the established minimum.

The invention is illustrated in conjunction with a lubricator of the type set forth in Letters Patent No. 1,066,238, granted to me under date of July 1, 1913.

40 In the drawings:

Figure 1 is a sectional elevation of so much of a lubricator as is necessary to an understanding of the invention;

Fig. 2 a like view of the adjusting stem or 45 rod, and the stop or locking quill;

Fig. 3 a disassembled view of said parts; and

Fig. 4 a detail view showing the parts in 50 a different adjustment from that illustrated in Fig. 1.

A suitable casing, as 1, is provided in which the parts are mounted and inclosed, a sight window or cover 2 being placed over the upper end of a tube or pipe 3 and the 55 cup 4 into which the tube discharges.

Pipe 3 at its lower end is in communication with the cylinder 5 of a measuring pump, while the tube 6, upon which cup 4 is mounted, is in communication with the cylinder 7 of a force pump by which the oil 60 is forced to the part or parts to be lubricated. Cylinder 7 is provided with a piston or plunger 8, having connected to its upper end, by a gimbal joint, a yoke 9. A strap 10 is swiveled in the yoke, said strap being 65 in engagement with an eccentric 11, through which a driving shaft 12 passes, this construction being similar to that disclosed in Letters Patent No. 796,659, dated August 8, 1905. Piston 8 also carries a sector gear 13, 70 which meshes with a similar shrouded gear 14, secured to the upper end of the piston or plunger 15 of the measuring pump.

Through the rotation of shaft 12, the eccentric causes the strap and yoke to be raised 75 and lowered and likewise imparts an oscillating movement to the yoke, which motions are transmitted to pistons 8 and 15 through the intermeshing gears 13 and 14. As a consequence, said pistons are raised and lowered and also oscillated, and inasmuch as they are provided with suitable intake and delivery ports the oil will be drawn in by the measuring piston 15 and forced to the 85 sight feed cup 4 and thence forced to the part to be lubricated, by piston 8.

To regulate the quantity of oil which may be drawn into the measuring pump or cylinder 5, a sleeve 16 extends upwardly into said cylinder, the sleeve surrounding piston 90 15 and operating in the manner set forth in Patent No. 1,066,238.

A laterally-extending arm 17 is rigidly secured to the lower end of said sleeve 16, and an adjusting rod 18 extends through 95 the arm, the parts having a threaded engagement. The rod extends upwardly through the casing and the outer end is preferably flattened for the application of a spanner or wrench. The rod extends through 100 a quill 19, which passes through a fixed member 20 of the lubricator frame, the quill having a threaded connection with said member, the pitch and direction of the thread being the same as that of the thread 105 on rod 18. Stop collars 21 and 22 are secured upon the rod and bear against the upper and lower ends, respectively, of the quill so that the rod may be said to be swiveled in the quill. A nut 23 is screwed 110

upon the lower end of the rod and serves to limit the downward movement of the arm 17, and to prevent the rod from being screwed out of the same.

5 In adjusting the device prior to the placement of the cover of the casing, the expert will turn the quill up or down, as the case may be, the rod 18 turning with it, without affecting the position of arm 17 and the 10 sleeve 16 as the rod turns in said arm. When elevated to the position shown in Fig. 1 the sleeve may be moved upwardly to a considerable extent in the cylinder, or until the arm 17 abuts the lower end of the stop 15 collar 22, beyond which it cannot move. This adjustment will allow a relatively small feed of oil by the measuring pump, and while such feed may be increased by turning the rod 18 to lower arm 17 and the attached 20 sleeve so as to increase the effective volume of the cylinder 5, it cannot be diminished beyond the fixed minimum.

In Fig. 4 the quill is shown in a lower position, and this would produce a larger 25 minimum flow than under the adjustment shown in Fig. 1. Under both adjustments of the quill the feed of oil may be increased, but it cannot be cut down below the predetermined minimum.

20) Inasmuch as the quill is inaccessible when

the cover is finally positioned, the inexperienced operator is precluded from varying the minimum amount of oil to be pumped to the part to be lubricated.

Having thus described my invention, what 35 I claim is:

1. In a force feed lubricator, the combination of a casing; a pump located therein; a sleeve adjustably mounted in the pump to vary the effective volume thereof; an arm 40 extending outwardly from the sleeve; a rod having a threaded connection with the arm and extending to a point without the casing; a quill surrounding the rod, the quill having a threaded connection with a fixed 45 portion of the lubricator and being located wholly within the casing; and collars secured upon the rod at the upper and lower ends of the quill.

2. In a force feed lubricator, the combination of a measuring pump; a forcing pump; gearing connecting the pistons of said pumps to cause them to oscillate in unison; a power device to actuate said gears and to raise and lower the pistons; and means for 50 controlling the capacity of the measuring pump.

In testimony whereof I have signed my name to this specification.

FRANK D. WINKLEY.
